[57] **CLAIM**

The ornamental design for a hand-held fingerprint scanner for imaging and capturing a photographic image, as shown and described.

DESCRIPTION

FIG. 1 is a top, front and right side perspective view of a hand held fingerprint scanner for imaging and capturing a photographic image showing our new design;
FIG. 2 is a rear elevational view thereof;
FIG. 3 is a front elevational view thereof;
FIG. 4 is a top plan view thereof;
FIG. 5 is a bottom plan view thereof; and,
FIG. 6 is a right side elevational view thereof, the side opposite that shown being a mirror image.

FIG. 1

FIG. 2**FIG. 3****FIG. 4**

FIG. 5

FIG. 6
